UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC-FURNACE RESISTOR.

Application filed December 2, 1922. Serial No. 604,507.

To all whom it may concern:

Be it known that I, ORA A. COLBY, a citizen of the United States, and a resident of Irwin, in the county of Westmoreland and 5 State of Pennsylvania, have invented a new and useful Improvement in Electric-Furnace Resistors, of which the following is a specification.

My invention relates to electric furnaces and particularly to electric resistance furnaces.

The object of my invention is to provide a relatively simple, compact and rugged electric heating element for an electric resistance furnace.

In practicing my invention, I provide a plurality of relatively thin, flat, refractory, electrical-conducting plates of substantially rectangular cross-section alternating with a 20 plurality of refractory electrical conducting bars of substantially I-beam section with their flat surfaces in operative engagement. Spaced refractory, electric-insulating, supporting plates operatively engage certain of 25 said flat plates to maintain the heating element in its proper operative position within a furnace chamber. Suitable resilient compressing means is provided to maintain the refractory electrical conducting elements in 30 close operative engagement.

In the single sheet of drawings.

Figure 1 is a view, in longitudinal vertical section, of an electric furnace comprising the device embodying my invention,

Fig. 2 is a view, in perspective, of one of the refractory members comprising a part of the heating element.

Fig. 3 is a view, in perspective, of a flat bar comprising another member of the heating element, and

Fig. 4 is a view in perspective of a refractory electric-insulating supporting member.

An electric furnace 11 comprises an outer metallic casing 12 having suitable supporting members 13 secured thereto. An outer lining 14 comprises a plurality of bricks or blocks of a suitable refractory heat-insulating material. An inner lining 15 comprises a plurality of bricks or blocks of a suitable 50 refractory high-temperature resisting material. The bricks or blocks comprising the two linings are so disposed as to provide a furnace chamber 16 of any suitable or desired contour and dimensions.

55 A heating element 17 for the furnace com-

prises a plurality of elongated flat plates or bars 18, alternating with a plurality of refractory electric conducting bars 19, of substantially I-beam section. The height of the plates or bars 18 is such as to permit of 60 the plates 18 being located within the overhanging flange portions of the members 19 with the flat surfaces of the respective members in close operative engagement.

An elongated refractory conducting electrode 21 extends through a suitable opening 22 in the furnace walls at each side thereof, with its inner end in operative engagement with one of the plates 18 or an end plate 23. A water-cooled electric-circuit terminal 70 member 24 operatively engages the outer tapering end of the electrode 21, being provided with a suitable co-operating opening therein. An electric-insulating member 25 comprising a ring of asbestos lumber is located within the outer surface of the end walls of the furnace surrounding the terminal member 24 to prevent leakage of current 75 therefrom to the furnace structure.

Compressing means for maintaining the 80 terminal member 24 in close operative engagement with the electrode 21 and for maintaining the plates and bars 18 and 19 under pressure, may comprise a screw-threaded rod 26, the inner enlarged end of 85 which rests against the outer surface of a block 27 of suitable electric-insulating material, operatively engaging the outer surface of the terminal member 24. A helical spring 28 surrounds the rod 26 over a portion of its length and has its outer end operatively engaging a fixed member 29, and its inner end engaging a washer 31 resting against an adjusting nut 32 which has screw threaded engagement with the rod 26. 95 While I have illustrated a specific embodiment of a compressing means, I do not desire to be limited thereto, as any suitable construction of such means may be employed.

In order to assist the resilient compressing means hereinbefore described in supporting the built-up heating element 17 in its proper operative position within the furnace chamber 16, I provide a plurality of spaced, refractory, electric-insulating, thin, flat plates 33 which operatively engage one or more of the plates 18 in the built up heating element 17.

An opening 34 is provided in each of the 110

plates 33 of substantially the same dimensions and contour as the plates 18 and wherever it is desired to employ the plates 33, I employ two plates 18 in adjacent relation, 5 instead of employing plates 18 and bars 19 alternately. The plates 33 are, of course, placed in their proper operative positions when and while the heating element is being built-up, before its installation as a complete 10 unit in the furnace chamber.

If desired, I may provide a refractory, electric-insulating plate 35 on the floor of the furnace chamber upon which the respective plates 33 may rest in order to insure 15 that little or no current shall flow between the spaced plates 33 through any circuit other than that of the built-up heating element.

If desired, the furnace chamber 16 may 20 be divided into a work-receiving compartment 36, and a heating compartment 37 by a refractory diaphragm 38, which may be supported in the furnace chamber by any suitable means, such as integral portions of 25 the inner lining 15. As this heating element is preferably employed in furnaces operating at relatively high temperatures, it is necessary to employ carbonaceous material for the plates and bars constituting the heating 30 element and these bars are oxidized by air entering the heating chamber during the operation of the furnace. Most of the air enters through the opening (not shown) into the work-receiving compartment and the use 35 of a refractory diaphragm reduces the oxidizing action of the entering air on the carbonaceous resistor members.

As the alternate resistor members are provided with overhanging flanges, any air entering the heating chamber 37 expends its 40 oxidizing action on the overhanging portions which protect the edges of the flat plates, whereby a longer life of the built-up

heating element is insured. The use of intermediate, spaced, supporting members makes 45 it possible to operate with less pressure of the resilient compressing means whereby a higher resistance of the built-up heating element is secured.

Various modifications and changes in detail and arrangement may be made without departing from the spirit and scope of the invention, and such modifications are intended to be covered by the appended claims.

I claim as my invention:

1. In an electric furnace, in combination, a resistor comprising a plurality of refractory electrical-conducting bars, of I-beam section, alternating with relatively thin flat refractory electrical-conducting bars interfitting with said bars of I-beam section and spaced refractory electrical-insulating supporting members operatively engaging said thin flat bars to support said resistor.

2. In an electric furnace, in combination, a resistor comprising a plurality of refractory electrical-conducting bars, alternately of rectangular and of I-beam section, interfitting and supporting each other, and a plurality of spaced thin refractory plates 70 operatively engaging certain of said bars to support said resistor.

3. In an electric furnace, in combination, a resistor comprising a plurality of refractory electrical-conducting bars, alternately 75 of rectangular and of I-beam section, interfitting and supporting each other, a plurality of spaced thin refractory plates operatively engaging certain of said bars to support said resistor and resilient means for maintaining all of said bars in close operative engagement.

In testimony whereof, I have hereunto subscribed my name this 27th day of November, 1922.

ORA A. COLBY.
